(57) **CLAIM**

The ornamental design for a champagne and caviar room, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is front view of the champagne and caviar room showing my new design.

The grayed-out areas surrounded by broken lines in the drawing, including any features contained therein when viewed in the front view of the sole FIGURE, depict portions of the champagne and caviar room that form no part of the claimed design.
